U.S. Appl. No. 16/391,294, filed Apr. 22, 2019, Bromwich et al.
(Continued)*Primary Examiner* — Cynthia M. Chin*(74) Attorney, Agent, or Firm* — Haynes and Boone, LLP(57) **CLAIM**

The ornamental design for a scooter, as shown and described.

DESCRIPTION

FIG. 1 is a top, rear, left side perspective view of a scooter showing our new design;

FIG. 2 is a left side elevation view thereof;

FIG. 3 is right side elevation view thereof;

FIG. 4 is a bottom plan view thereof;

FIG. 5 is a top plan view thereof;

FIG. 6 is a front elevation view thereof; and,

FIG. 7 is a rear elevation view thereof.

The dash-dot broken lines adjacent to the shaded areas represent boundaries of the claimed design and form no part thereof. All other broken lines are for the purpose of illustrating portions of the article that form no part of the claim.

1 Claim, 5 Drawing Sheets(56)
